METHOD OF MAKING PISTON RINGS

Douglas W. Hamm, Muskegon, Mich., assignor to
 Muskegon Piston Ring Company, Muskegon,
 Mich., a corporation of Michigan

Application March 8, 1952, Serial No. 275,515

7 Claims. (Cl. 148—12.4)

1

This invention relates to a novel and very practical and useful method of producing a circumferentially compressible piston ring. The compressible ring, usually of thin spring-like metal has been known for a considerable time, and the practice employed in making it requires a blanking or shearing operation to outline and produce a continuous series of segmental sections, one at the upper side of the ring and one at the lower side thereof, the segments in the completed ring, having a very considerable degree of independent action in connection with the total ring action. As the edges of the blank of the material used for the ring are straight, and as such edges become the outside edges of the ring, the ring must be ground or finished circular on the outside diameter after forming in order to change, from a chord to an arc, the edges of those parts of the segments which contact the cylinder wall.

With my invention the ring is formed in circular form before dividing or separating the consecutive series of segmental sections. Thereafter, the ring flanges or lands which are in circular form and are continuous in length are broken or fractured transversely at selected proper points in the length to obtain the final structure of generally independent land segments or sections. No material is removed in such breaking.

The breaking is accomplished preferably by heat treating the formed ring, which is of a proper ferrous composition that it may be hardened, so that the material is of a hardness of approximately 65 Rockwell "C" scale. Such material is brittle, or, as it is known, "glass hard" and slight impact or pressure causes the ring to break in the exact locations desired which may, preferably, be preselected by grooving or notching the material at one side where the breaks are to occur.

After breaking has been done, the ring is then heat treated to reduce the hardness so that it will have desired physical properties and characteristics. As the ring has been formed circularly, no grinding on the outside diameter is required. Rings having narrow lands can be practically produced by having the proper narrow width stocks to start with. In my invention and the method used, accurate control of the closure gap of a parted ring is maintained, and the gaps or spaces between consecutive ring segments may be made smaller than has previously been practical.

The invention is useable not only to make parted circumferentially compressible rings, but

2

also rings which are continuous having no partings.

An understanding of the invention may be had from the following description, taken in connection with the accompanying drawings, in which,

Fig. 1 is a perspective view of a length of flat, ribbon material from which a parted circumferentially compressible piston ring may be made.

Fig. 2 is an enlarged plan view thereof after the first step in the operation, which consists in striking from the length of material a consecutive series of spaced transverse openings separated from each other and, preferably, grooving or notching from opposite ends of alternate openings scoring breaking lines of the material to or toward the outer edges thereof.

Figs. 3 and 4 are fragmentary longitudinal sections substantially on the planes of lines 3—3 and 4—4 of Fig. 2.

Fig. 5 is a fragmentary perspective view of a portion of a length of the ring after the side flanges have been turned at right angles to the connecting web portions thereof.

Fig. 6 is a plan view, partly in dash line, and 25 with the remainder partly in plan and partly in intermediate horizontal section of the formed circular ring which is produced, after the second step of the operation to produce the ring flanges as in Fig. 5.

Fig. 7 is a fragmentary enlarged outer edge elevation of the formed ring shown in Fig. 6 before breaking the flanges into a consecutive series of land segments.

Fig. 8 is a like view after such breaking, which 35 is preferably substantially upon the notched or scored grooves between the outer edges of the rings and the openings therethrough.

Fig. 9 is a partial plan and partial intermediate longitudinal section, enlarged, through a fragmentary portion of the completed ring after the 40 segment breaking separation.

Fig. 10 is an elevation showing the first step of operation of producing a circular grooved continuous ring from tubular stock.

Fig. 11 is a similar elevation showing the manner in which such circular ring having the channel cross section is cut from the tube.

Fig. 12 is a plan view showing the circular ring in outline after the succeeding step of the operation, which consists in milling separated vertical slots in the inside diameter web of the rings cut from the tubular stock, and providing the notched or depressed breaking grooves therein, and

55 Figs. 13 and 14 are views similar to Figs. 7 and

8 showing inner elevations of fragmentary portions of the ring, the one before the segment separation by breaking has occurred, and the other after it has taken place.

Like reference characters refer to like parts in the different figures of the drawings.

With my method, the length of flat thin metal ribbon stock indicated at 1 which may be of the length of one ring, but in practice is generally elongated so as to produce a plurality of rings which may be separated one from the other, is first subjected to punching operations to strike therefrom elongated transverse openings 2 longitudinally spaced from each other, having their ends inwardly of the opposite edges of the strip of metal 1. Alternate openings 2 at opposite ends thereof also, preferably, have shallow grooves 3 pressed therein extending from selected ends of the openings 2 with which associated to the adjacent longitudinal edge of the metal strip 1. Between successive grooves 3 at both side edges of the ring there will be defined segments 4 at both side edges of the metal strip, and the successive openings 2 are spaced from each other by what in the completed ring will be connecting webs 5 extending between the segments 4 at opposite sides of the ring.

The flat metal strip processed as described and as shown in Fig. 2, is thereafter formed into a circular form and with the longitudinal side edge portions turned in the same direction from the connecting webs 5 to parallel each other, making a substantially continuous circular channel in which the connecting web portions 5 at the inner curved side of the channel are separated from each other by the openings 2.

After the ring has reached the circular form substantially as in Fig. 6, it is heat treated and quenched so that the material, which is preferably of a relatively high carbon steel having substantially 90% carbon content (not necessarily closely restricted thereto) is "glass hard," and may have a hardness of approximately 65 Rockwell "C" scale. Such hard material is brittle and is readily broken by light pressure or flexing at the grooves 3. Even if the grooves are not used the breaking will occur in the narrower widths of the material between the ends of the slots 2 and the adjacent edges of the formed circular ring. However, care would have to be exercised to see that such breakage occurred with successive openings 2 alternately at opposite ends of such openings.

The ring after the successive land segments 4 have been thus separated is again heat treated to reduce hardness and temper to the desired degree, so that the finished and completed ring is properly wear resistant and resistant to breakage, that is, have substantially the same physical properties of piston rings of this type which are now made and sold. The two ends of the ring will come together and abut at a parting, indicated at 7 in Figs. 6 and 9 and the adjacent ends of successive segments 4 are slightly separated by narrow slots 6. In order to obtain the slots 6 of the required narrow width, it may be necessary to stretch the completed ring over a mandrel or by other process, the diameter of the completed ring in its free state being larger than the interior diameter of a cylinder in which it is to be used, the ring being circumferentially compressed to reduce its outside diameter and close the gaps at 6 to substantially completely closed position.

In Figs. 10, 11 and 12, from a tube 8 of steel

having the proper carbon content, rings of channel cross section are successively cut, each having a groove 9 which is first machined by a proper cutting tool 10 before the ring is separated from the tube 8 by a cutting tool 11, the groove 9 being between opposed annular flanges 12 of the channel shaped ring. Such ring having no parting is then milled at its inner side to cut a consecutive series of spaced slots 2 extending between the flanges, the slots being cut through the web of the channel ring form and leaving web portions 5 between the segmental portions 4 which with this way of making the ring may be defined at their ends by similar grooves 3 reaching from opposite ends of alternate slots 2 to the outer edges of the channel sides 12. Said grooves 3 can be made at the outer sides of the flanges 12 as well as at the inner sides, and will provide weakened breaking lines for the ring after it has been heat treated and hardened the same as described with reference to the parted ring structure shown in Figs. 1 to 9 inclusive. The tempering and hardening and the succeeding heat treatment and reduction of hardness after the breaking has taken place, and such stretching as may be needed, follows the same steps as previously described.

The continuous ring having no parting at its side may be installed over a piston by stretching it over the piston instead of the present conventional installation of spreading the ends of a ring apart, and placing it in the ring groove of a piston.

The process or method of forming circumferentially compressible steel piston rings has the advantages previously recited, particularly that of ability to more accurately control the spaces between the adjacent ends of successive segments in both the upper and lower sides of the ring, and the parting width in a parted ring, so that when the ring is compressed and held in compressed condition upon installing in an engine cylinder, the gaps between adjacent ends of the segments may be held to extremely close limits. Also there is elimination of the step of grinding the ring to circular form at its outside diameter, and the width of the ring lands may be made much narrower than has previously been practically possible.

Having now fully described my invention what I desire to claim and secure by Letters Patent is as follows:

1. The method of making a circumferentially compressible piston ring consisting in providing a circular ring member of thin steel material of channel cross section, having upper and lower spaced parallel continuous horizontal flanges and a vertical connecting web, said web having a successive series of closely spaced generally vertical slots, with generally vertical web portions between said slots, heat treating and hardening said member to a brittle, easily fractured condition, fracturing each flange from its free edge to the adjacent ends of alternate slots, and thereafter again heat treating the ring member to reduce hardness thereof.

2. The method of making a circumferentially compressible piston ring consisting in, providing a circular ring member of thin steel material of channel cross section having upper and lower parallel, continuous horizontal flanges, and an integral generally vertical connecting web between said flanges, said web having a successive series of equally spaced, generally vertical slots between spaced web portions, said slots at upper

and lower ends extending into the flanges at the inner portions thereof, heat treating and quenching said ring member to harden it to brittle, easily fractured condition, fracturing each flange from its outer edge to the adjacent ends of alternate slots, the fractures in one flange being staggered with respect to the fractures in the other flange, and again heat treating the ring member to reduce hardness thereof.

3. The method of making a circumferentially compressible piston ring consisting in, providing a circular ring member of thin steel material of channel cross section having upper and lower parallel, continuous horizontal flanges and an integral, generally vertical connecting web between said flanges, said web having a continuous and consecutive series of openings spaced lengthwise of the web, with web connecting portions between said openings connecting said flanges, heat treating and quenching the ring member to harden it to a brittle easily fractured condition, fracturing each flange transversely from its free edge to adjacent openings, and again heat treating the ring member to reduce its hardness.

4. The method having the process steps defined in claim 2, and stretching the ring member circumferentially after the last heat treatment thereof.

5. The method having the process steps defined in claim 3, and widening the breaks in said flanges where fractured, after the last heat treatment of the ring member.

6. The method having the process steps defined

in claim 3, and weakening the metal in the said flanges, at preselected points in the flanges where fracture thereof is wanted, before the first heat treatment and hardening of the ring member.

- 5 7. The method of making a circumferentially compressible piston ring consisting in, removing from a thin elongated strip of steel ribbon material having parallel side edges, metal in an elongated zone substantially midway between the side edges to make a consecutive series of spaced openings, in length substantially at right angles the length of the strip, bending the side edge portions of the strip in the same direction and the entire strip into substantially circular channel cross sectional form, having continuous spaced flanges to provide a ring member, heating and quenching the ring member to harden it to a brittle, easily fractured condition, fracturing said flanges from the outer edges thereof to the adjacent ends of alternate openings, the fractures in one flange being staggered with respect to the fractures in the other flange, and again heat treating said ring member to reduce hardness thereof.
